UNITED STATES PATENT OFFICE

JAY A. HEIDBRINK, OF MINNEAPOLIS, MINNESOTA

ANÆSTHETIZING APPARATUS

Application filed February 23, 1924. Serial No. 694,486.

My invention relates to anaesthetizing apparatus and particularly to apparatus of this kind for use in obstetrical cases in which it is generally desirable to administer anaesthetizing gases, and sometimes pure oxygen to the prospective mother, and in which it is often desirable to administer pure oxygen to the child after birth. An object of the invention is to provide an apparatus by means of which a plurality of gases such as oxygen and nitrous oxid may be readily delivered from sources of supply in the following different ways.

1. A properly proportioned nitrous oxid-oxygen mixture may be delivered to a customary or main inhaler.

2. Pure nitrous oxide may be delivered to a main inhaler.

3. Pure oxygen may be delivered to the main inhaler.

4. Pure oxygen may be delivered to a baby inhaler only.

5. Pure oxygen may be delivered to a baby inhaler and a mixture of oxygen and nitrous oxid be delivered at the same time to the main inhaler.

The full objects and advantages of my invention will appear in connection with the detailed description, and the novel features of my inventive idea will be particularly pointed out in the claims.

In the accompanying drawings which illustrate one form in which my invention may be embodied, Fig. 1 is a plan view of the apparatus with a small portion thereof shown in section. Fig. 2 is a view in section on the line 2—2 of Fig. 4. Fig. 3 is a view in section on the line 3—3 of Fig. 1. Fig. 4 is a view in section on the line 4—4 of Fig. 2. Fig. 5 is a view mostly in section on the line 5—5 of Fig. 1. Fig. 6 is a view in section on the line 6—6 of Fig. 2. Fig. 7 is a view in section and on reduced scale on the line 7—7 of Fig. 4. Fig. 8 is a view in section on the line 8—8 of Fig. 2. Fig. 9 is a view in section on the line 9—9 of Fig. 10. Fig. 10 is a view in section on the line 10—10 of Fig. 9. Fig. 11 is a view in section on the line 11—11 of Fig. 12. Fig. 12 is a view in section on the line 12—12 of Fig. 11.

As shown in the drawings, there is a pair of arms 14, 16, the outer ends of which are provided with yokes 18 and 20 within which the heads of gas containers 22 and 24 are adapted to be secured by set screws 26 and 28. The container 22 is intended for holding oxygen and the container 24 is intended for holding nitrous-oxid. The arms 14 and 16 contain longitudinal passageways 30 and 32 as shown in Fig. 3 with which the gas containers are adapted to be placed in communication by means of needle valves 34 and 36 and which communicate with the reducing valves. The arms 14, 16 extend out from a central member 38. Controlling devices designated in general by the numerals 40 and 42 are arranged for cooperation with the passageways 30 and 32, the inner ends of which communicate with downwardly turned perforations 44 and 46 formed in blocks 48 and 50, rigidly secured in tubular members 52 and 54 forming part of the controlling devices 40 and 42 and formed integrally with the member 38. Slidable blocks 56 and 58 are placed in the tubular members 52 and 54 and the upper ends of these blocks have annular flanges 60 and 62 containing fiber plugs adapted to engage the outlet ends of the perforations 44 and 46. The blocks 56 and 58 are held resiliently upward by springs 64 and 66, and these blocks may be depressed by staplelike members 68 and 70 which extend loosely through openings formed in the fixed blocks 48 and 50. The staples 68 and 70 at their upper ends are engaged by the lower surfaces of diaphragms 72 and 74 forming the upper walls of chambers 76 and 78. Coiled springs 80 and 82 rest upon the upper surfaces of the diaphragms 72 and 74 and the tension of these springs may be regulated by screws 84 and 86. There are a pair of lugs 88 and 90 formed on the front of the central member as best shown in Fig. 7. These lugs have openings in communication with the chambers 76 and 78 and these openings are screwthreaded to receive the upper ends of tubes 92 and 94 having lower enlarged portions 96 and 98 threaded into which are cap members having flanged heads 100 and 102 as clearly shown in Figs. 4 and 6. A valve casing 104 has arms 106

106, 108 through openings in which the tubes 92 and 94 extend, the upper sides of the arms being engaged by the lugs 88 and 90 and the lower sides of the arms being engaged by shoulders on the enlarged tubular portions 5 96 and 98. The arms 106 and 108 contain passageways 110 and 112, the rear ends of which are in communication with ports 114 and 116 in the tubes 92 and 94. The passageway 112 leads into a chamber 118 in the valve casing 104 as shown in Fig. 4 and the passageway 110 leads into a space 120 in the valve casing above the chamber 118 as shown in Fig. 6, the said space and chamber being 10 separated by a wall having an opening provided with a tube 122 extending down into the chamber 118. The upper end of the tube 122 constitutes a valve seat for a valve 124 having a stem 126 extending down through 15 the tube 122. The upper portion of this tube has an enlarged bore so that when the valve 124 is lifted from its seat, the space 120 is in communication with a port 128 opening into the chamber 118. A disk 130 is secured to the 20 lower end of the valve stem 126 and this disk rests upon the upper surface of a diaphragm 132 which constitutes the lower wall of the chamber 118. The disk 130 has an opening in which a pin 134 fits with sliding engagement so that this disk is guided for up and 25 down movements, the disk being held down normally by a coiled spring 135. Underneath the diaphragm 132 is a space in communication with the hollow interior of a tubular member 136 having a flanged head 138. The member 136 has inlet ports 140 connected by a tube 142 with outlet ports 144 in the cap member which is connected with the tube 94 as shown in Fig. 4. The tube 142 is held in place 30 by the flanged heads 102 and 138. The chamber 118 constitutes a mixing chamber and it has an outlet port 146 surrounded by a nipple 148 which in use of the apparatus is connected by suitable tubing with an inhaler, it being understood that a customary rebreathing bag may be attached at any suitable place 35 in this connection and that a well known shutoff valve is provided. An auxiliary valve casing 150 is attached to the main valve casing 104 and this auxiliary casing contains a hollow plug valve 152 having an operating handle 154. The auxiliary casing 150 contains a passageway 158, leading to an inlet port 158 in the main casing 104. The auxiliary casing 150 contains a second passageway 160 which is in communication with the interior of a tubular member 162 into the lower end of which is threaded a cap member having a flanged head 164. Inlet ports 50 166 in the cap portion of the tubular member 162 are connected by a tube 168 with outlet ports 170 in the cap member attached to the tube 92 leading from the oxygen chamber 76. The plug valve 152 is provided with a pair of 55 upper ports 172 and 174 either one of which

may be brought into register with the passageway 160 when the plug valve is turned through 180°. The plug valve is provided with a lower port 176 which is directly beneath the port 172 and which registers with the passageway 156 leading to the mixing chamber 118 when the plug valve is in the position shown in Fig. 8. The plug valve is further provided with an intermediate port 178 extending at right angles to the port 172 and 70 174 and adapted when the plug valve is in the position shown in Fig. 12, to register with a passageway 180 in the casing 150 and leading through a nipple 182 adapted to be connected by a small tube with an inhaler 75 for administering oxygen to a baby. The oxygen chamber 76 is connected by a pipe 184 with a gauge 186 which registers the percentage of oxygen in the mixture when a mixture of oxygen and nitrous oxid is administered. The nitrous oxid chamber 78 is connected by a pipe 188 with a gauge 190 which registers the number of gallons of nitrous oxid delivered per minute. 80

The operation and advantages of my invention will now be readily understood. In the embodiment shown, the apparatus is adapted to be placed flat upon the bed and does not require any standard or similar support. When it is desired to administer a 90 mixture of oxygen and nitrous oxid to the patient, the plug valve 152 is in the position shown in Figs. 9 and 10 so that oxygen cannot get past this valve. The nitrous oxid which is admitted passes into the nitrous oxid chamber 78 from which as will be apparent from Fig. 4 it goes through the passageway 112 into the mixing chamber 118. The pressure of the nitrous oxid acting through the ports 140 and 144 and tube 142 is exerted 95 upon the lower surface of the diaphragm 132, thereby lifting the valve 124 and admitting oxygen into the mixing chamber when the shutoff valve is opened, whereby the pressure in the chamber 118 is reduced, the amount of oxygen being determined by the lift of the valve, and hence being proportionate to the pressure of the nitrous oxid and the number of gallons thereof delivered 100 per minute and indicated on the gauge 190. The amount of oxygen will be automatically increased or decreased in proper proportion to any increase or decrease in the delivery of nitrous oxid and the percentage of oxygen in the mixture will be indicated on the gauge 186. By referring to Fig. 6, it will be seen that the oxygen passes from the oxygen chamber 76 through the passageway 110 to the space above the valve 124. In order 105 to deliver pure nitrous oxid, it is merely necessary to shut off the supply of oxygen. In order to deliver pure oxygen, however, it is not sufficient merely to shut off the supply of nitrous oxid since the pressure of the latter 110 causes the proper percentage of oxygen to be 115

supplied and the shutting off of the nitrous oxid also shuts off all supply of oxygen past the valve 124. Therefore, the plug valve 152 is turned into the position shown in Fig. 8 whereupon oxygen flows through this valve and passes into the chamber 118 for delivery to the inhaler. When it is desired to administer pure oxygen to the child, the plug valve 152 is turned into the position shown in Figs. 11 and 12 whereupon oxygen passes through this valve into the passageway 180 and thence to the baby inhaler. It is obvious that when pure oxygen is being delivered in this way to the baby inhaler, the mixture of oxygen and nitrous oxid may at the same time be delivered from the mixing chamber 148 to the main inhaler.

I claim:

1. An anæsthetizing apparatus having a mixing chamber, means for supplying thereto from independent sources of supply a plurality of gases under pressure, a connection for an inhaler leading from said mixing chamber, means for shutting off the supply of gases to said mixing chamber, a valve casing, an adjustable valve in said casing, a passageway connecting said valve casing with one of said sources, a passageway connecting said valve casing with said mixing chamber, and a connection for a second inhaler leading from said valve casing, said valve having ports so arranged that for different positions thereof gas from said last mentioned source may be delivered into said second inhaler or into said last mentioned passageway as desired.

2. An anæsthetizing apparatus having a mixing chamber, means for supplying thereto nitrous oxid and oxygen from independent sources of supply, a connection for an inhaler leading from said mixing chamber, means for shutting off the supply of gases to said mixing chamber, a valve casing, a rotatable plug valve in said casing, a passageway leading from the source of supply of oxygen to said plug valve, a passageway leading from said plug valve to said mixing chamber, and a connection for a second inhaler leading from said valve casing, said rotatable plug valve containing ports so arranged that for different positions thereof oxygen may be delivered through said casing into said second inhaler connection or into said last mentioned passageway or may be shut off from passing through said auxiliary casing as desired.

3. An anæsthetizing apparatus having a mixing chamber, means for supplying thereto nitrous oxid and oxygen from independent sources of supply, controlling devices for the passages leading to said mixing chamber, said controlling devices containing gas chambers for nitrous oxid and oxygen respectively, a main casing containing said mixing chamber, a main inhaler connection

leading from said mixing chamber, a passageway leading from said nitrous oxid chamber to said mixing chamber, a valve controlling an opening for oxygen into said mixing chamber, means for causing said valve to be opened to an extent in proportion to the pressure of gas in said nitrous oxid chamber, a passageway leading from said oxygen chamber to said valve, an auxiliary casing, a rotatable plug valve in said casing, a passageway leading from said oxygen chamber to said plug valve, a passageway leading from said plug valve to said mixing chamber, and a baby inhaler connection leading from said auxiliary casing, said rotatable plug valve containing ports so arranged that for different positions thereof oxygen may be delivered through said auxiliary casing into said baby inhaler connection or into said last mentioned passageway, or may be shut off from passing through said auxiliary casing as desired.

4. An anæsthetizing apparatus having a mixing chamber, means for supplying thereto nitrous oxid and oxygen from independent sources of supply, controlling devices for the passages leading to said mixing chamber, said controlling devices containing gas chambers for nitrous oxid and oxygen respectively, a main casing containing said mixing chamber, a diaphragm constituting one of the walls of said mixing chamber, a passageway leading from said nitrous oxid chamber into said mixing chamber, a main inhaler connection leading from said mixing chamber, a passageway leading from said nitrous oxid chamber to the outside surface of said diaphragm, a valve controlling an opening for oxygen into said mixing chamber, a spring normally maintaining said valve seated, connections between said diaphragm and said valve for causing the latter to be opened to an extent in proportion to the pressure of nitrous oxid on said diaphragm, a passageway leading from said oxygen chamber to said valve, an auxiliary casing, a rotatable plug valve in said casing, a passageway leading from said oxygen chamber to said plug valve, a passageway leading from said plug valve to said mixing chamber, and a baby inhaler connection leading from said auxiliary casing, said rotatable plug valve containing ports so arranged that for different positions thereof oxygen may be delivered through said auxiliary casing into said baby inhaler connection or into said last mentioned passageway or may be shut off from passing through said auxiliary casing as desired.

5. An anæsthetizing apparatus comprising a mixing chamber, means for supplying thereto from independent sources of supply two gases under pressure, a casing containing said mixing chamber, a diaphragm constituting one of the walls of said mixing chamber, a restricted passageway for conducting

one of said gases into said mixing chamber, a second passageway for conducting the same gas to the outside surface of said diaphragm, a valve controlling a passageway for conducting the other of said gases into said mixing chamber, means normally maintaining said valve seated, connections between said diaphragm and said valve for causing the latter to be opened to an extent in proportion to the pressure of gas passing through said second passageway, and a passageway leading from said mixing chamber for supplying the mixed gases to an inhaler.

6. An anæsthetizing apparatus having a mixing chamber, means for supplying thereto from independent sources of supply two gases under pressure, controlling devices for the passageways leading to said mixing chamber, said controlling devices containing gas chambers for the two gases respectively, a casing containing said mixing chamber, a diaphragm constituting one of the walls of said mixing chamber, a restricted passageway leading from one of said chambers into said mixing chamber, a second passageway leading from said last mentioned chamber to the outside surface of said diaphragm, a valve controlling a passageway from the other of said chambers into said mixing chamber, means normally maintaining said valve seated, connections between said diaphragm and said valve for causing the latter to be opened to an extent in proportion to the pressure of gas passing through said second passageway, and a passageway leading from said mixing chamber for supplying the mixed gases to an inhaler.

7. An anæsthetizing apparatus having a mixing chamber, means for supplying thereto nitrous oxid and oxygen from independent sources of supply, controlling devices for the passages leading to said mixing chamber, said controlling devices containing gas chambers for nitrous oxid and oxygen respectively, a casing containing said mixing chamber, a diaphragm constituting one of the walls of said mixing chamber, a restricted passageway leading from said nitrous oxid chamber into said mixing chamber, an inhaler connection leading from said mixing chamber, a passageway leading from said nitrous oxid chamber to the outside surface of said diaphragm, a valve controlling an opening for oxygen into said mixing chamber, a spring normally maintaining said valve seated, and connections between said diaphragm and said valve for causing the latter to be opened to an extent in proportion to the pressure of nitrous oxid on said diaphragm.

60 In testimony whereof I hereunto affix my signature.

JAY A. HEIDBRINK.
